UNITED STATES PATENT OFFICE.

ANDREW McCORMICK, OF NASHVILLE, ARKANSAS.

WATER PREHEATER FOR BOILERS.

Application filed March 12, 1923. Serial No. 624,426.

To all whom it may concern:

Be it known that I, ANDREW McCORMICK, a citizen of the United States, and a resident of the city of Nashville, county of 5 Howard, and State of Arkansas, have invented certain new and useful Improvements in Water Preheaters for Boilers, of which the following is a specification.

My invention relates to water preheaters 10 for boilers, and more particularly to means for utilizing exhaust steam from various auxiliary appliances upon a locomotive, such as the headlight motor, the pump, or similar devices, for preheating feed water before its delivery to the locomotive boiler.

Other objects will appear hereinafter.

The invention consists in the combinations and arrangements of parts hereinafter described and claimed.

20 The invention will be best understood by reference to the accompanying drawings forming a part of this specification, and in which,

Fig. 1, is a side elevation of a locomotive 25 showing the preheating means applied thereto, parts of the locomotive and preheating means being broken away to more clearly illustrate the construction and application of the invention,

30 Fig. 2, is an enlarged fragmentary view of the connection between the auxiliary heating means of the device and the preheating feeding means,

Fig. 3, is a fragmentary rear elevation 35 of a locomotive boiler showing the invention applied thereto, and

Fig. 4, is a sectional view of the invention taken on line 4—4 of Fig. 1.

Referring to the drawings 5 represents 40 a locomotive boiler having the usual fire box 6, water chamber 7, fire tubes 8 and smoke stack 9. The locomotive may also be equipped with a steam driven headlight motor 10 and pump 11, as well as other 45 steam driven devices not shown, all in the ordinary manner.

The invention comprises a heater casing 12 in the form of a hollow cylinder, and 50 preferably disposed at one side of the locomotive and secured to the running board 13 thereof by means of suitable brackets 14; and a similar casing 15 is preferably mounted upon the running board 16 at the opposite side of the locomotive in a similar manner. The casings 12 and 15 preferably are

in communication with each other by means of a pipe 17 which connects the forward ends of such casings. Preferably communicating with the casing 12, at the rear end thereof, is an exhaust pipe 18 leading to the pump 11, and an exhaust pipe 19 leading to the headlight motor 10. The heater casing 15 is provided with an outlet pipe 20 at its rear end which preferably extends to and opens into the smoke stack 9, so that exhaust steam from the pipes 18 and 19 flows into the rear end of the casing 12, passes forwardly therein and into the casing 15 by means of the pipe 17, emerging from the casing 15 at its rear end and being conducted to the smoke stack 9 by means of the pipe 20.

Disposed within the heater casing 12 is a coil 21, the end 22 of which is connected to a suitable device such as a steam injector 23 of a type ordinarily used to force water into the boiler, there also being a feed pipe 24 communicating with a water supply and connected to the injector in the ordinary manner. The other end 25 of the coil 21 is connected to a check valve 26 of any well known construction, such check valve having a nozzle 27 leading into the water chamber 7 of the locomotive. The rear end of the casing 12 may be provided with suitable glands for rendering the casing steam tight and at the same time permitting expansion and contraction of the coil ends. The heater casing 15 is also provided with a coil similar to the coil 21, having its end 28 connected to an injector 29, or other suitable device, the opposite end 30 of said coil being connected to a check valve 31 of ordinary construction which communicates with the water chamber 7 of the locomotive in the same manner as described for the valve 26, the construction of the two casings and parts being identical. The heater casings 12 and 15, the pipes, and the parts of the device are preferably covered with suitable heat retaining material as shown at 34.

A steam pipe 32 may be connected with a head having distributing valves 33, for the purpose of delivering steam to the injectors 23 and 29 in the ordinary manner. By this arrangement the exhaust steam from the steam motor 10 and pump 11 or other steam driven devices, not shown, is delivered into the rear end of the casing 12 passing from such casing through the pipe 17, entering

the casing 15, and emerging therefrom at the rear end, from whence it is conducted to the smoke stack or other suitable outlet by means of the pipe 20. When it is desired to feed water through the heating coils, the water from the pipes 24 is admitted to the injectors 23 and 29, which force it through the coils in the casings 12 and 15, and through the check valves 26 and 31 into the water chamber 7 of the locomotive.

Extending through the fire box 6, side by side, are pipes of any suitable size and material, one of which is shown at 35 in Figs. 1 and 2, the outer end of the pipe 35 being disposed opposite to and slightly spaced from the nozzle 27 of the check valve 26, the other pipe, not shown, being disposed opposite and slightly spaced from the nozzle of the check valve 31, the inner ends of such pipes communicating with the water chamber 7 of the boiler. By this arrangement when the injectors are not operating, and no feed water is being delivered to the boiler, the fact that the pipes are spaced from the nozzles of the valves 26 and 31 will permit a free circulation of water through such pipes. When the injectors operate to force the water through the coils and through the check valves 26 and 31, the nozzles of the valves will deliver the water to the water chamber at the far side of the fire box 6 through the pipes disposed in the fire box, thereby heating the water to a high temperature.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. The combination with a locomotive having a boiler; a heater casing mounted at each side of said locomotive; a pipe extending through said locomotive and connecting the forward ends of said casings with each other; auxiliary steam driven devices upon said locomotive; means for introducing the exhaust steam from said devices into one of said casings, said steam flowing through said casing and pipe and into and through the other casing; a pipe extending from the last said casing into the smoke stack; a coil disposed in each of said casings and leading into the rear of said boiler; and means for forcing water through said coils into said boiler.

2. The combination with a locomotive having a boiler; a heater casing mounted at each side of said locomotive; a pipe extending through said locomotive and connecting the forward ends of said casings with each other; a steam operated air-pump and head-light motor mounted on said locomotive; means for introducing the exhaust steam from said pump and motor into the rear end of one of said casings, said steam flowing through said casing and pipe into and through the other casing; a pipe extending from the last said casing into the smoke stack to lead the exhaust steam thereinto; injectors mounted on said locomotive; and heating coils mounted in said heater casings, one end of each of said coils being connected with an injector, the opposite ends of said coils being provided with nozzles extending into the water chamber through the rear wall of said boiler.

In testimony whereof I have signed my name to this specification.

ANDREW McCORMICK.
